Application June 29, 1935, Serial No. 28,998

22 Claims. (Cl. 200—48)

This invention relates to switches, and more particularly to switches designed for high ampere capacity and employed in high tension electrical transmission lines.

5 In switches of this type as heretofore provided, of which we are aware, the switches were commonly provided with flat bars presenting a relatively large contact surface. Such switches, based upon this design, were built both with and 10 without means for applying and releasing the pressure at the contacts. It is apparent that with such a construction, even if provided with pressure applying means, it was necessary to provide for accurate alignment of the contacts, blade bar 15 and hinge, in order to eliminate, to as large extent as possible, any localized points of contact. This localizing of contact areas becomes a serious matter if any substantial misalignment is present in switches of this type.

20 To overcome this disadvantage, switches have been designed with some form of restricted contact areas, and usually these switches are also provided with some type of mechanical means for applying pressure to the contact areas after 25 movement of the switch blades into operative position. With such switches, the necessity for accurate alignment of the contacting surfaces is not as essential as in switches utilizing a flat contacting area.

30 It is the object of the present invention to provide a high ampere capacity switch of this general type, having restricted line contact areas formed on the blade members only, which are adapted to move across the surface of the contact 35 bars as the switch blade is moved into operating position, thereby providing a wiping contact that will maintain the contact surfaces clean and will reduce the electrical resistance therethrough. In this connection, the contact areas on the blades 40 may be angled with respect to the arc of movement of the blades to prevent wearing of a groove into the contact bar surfaces.

In prior art switches of the pressure contact type, considerable difficulty has been encountered 45 in that the pressure is entirely released at the hinge as well as at the contact so that when the blade is swung to open position, it is so loosely supported that it rattles and vibrates, which is an objectionable condition. Since in this type of 50 switch a multi-blade construction is desirable, vibration between the blades themselves and between the blades and the hinge is possible.

In prior types of high amperage capacity switches with which we are familiar, it is impossible to provide any means for guiding the 55

blades into proper relation with the contact bars as the switch is being closed, and consequently, if there is any lost motion or play at the hinge connection, there is danger of the blade bars striking the contact bars rather than entering between them. 5

The present invention overcomes these difficulties by providing a construction wherein the pressure at the hinge is not released entirely when the pressure at the contacts is released prior to movement of the blades out of operating position. Thus, upon release of the pressure contact between the blades and the contact bars, the pressure at the hinge holds the blades against vibration or rattling, both when the blades are still 10 in operative position, and also after they have been moved away from the contact bars into inoperative position. Also, the line contacts at the hinge end of the blades are disposed on both 15 sides of the hinge bolts, and the blades are thus held in alignment and no difficulty is experienced 20 as they are moved toward and away from the contact bars.

Another object of the present invention is to provide for application of pressure to both the hinge and contact by means of right and left hand threaded studs interconnected by a single 25 rod, whereby rotation of the threaded studs moves the correspondingly threaded bushings which hold the blade bars in position, to increase or decrease 30 the pressure at the hinge and contact. In this connection, we also provide adjustable means for producing any desired operating pressures at both the hinge and the contact. 35

A further object of the present invention is to provide a differential rate of increase or decrease 40 of pressure at the hinge and contact, so that pressure at the hinge is not entirely released though pressure at the contact is completely released. We accomplish this by a novel arrangement of interconnecting linkage which produces different angular rotation of the hinge and contact studs so that when pressure at the contact 45 is completely released there still remains sufficient pressure at the hinge to prevent rattling and misalignment of the blades.

Another novel feature of the present invention resides in the provision of a toggle action between the switch operating member and the link interconnecting the threaded studs, whereby the contact pressure can be retained after movement of the operating member into locking position without the necessity of providing additional locking means. This toggle action is such as to prevent 50 55

release of the contact pressure upon ordinary vibration of the switch supporting structure.

Still another feature of the present invention is provided by the latching mechanism disposed between the operating member and the blade hinge, whereby during initial rotation of the operating member the blades remain in their operative positions, the contact pressure and the hinge pressure being differentially released, and upon further movement of the operating member the latching mechanism is engaged to prevent further release of pressure at the contact and hinge ends of the blade bars and to provide for conjoint movement of the blades about the hinge out of operative position.

In the practical application of switches of this type it is essential to have a relatively high pressure between the blade bars and the hinge and contact bars when the switch is in the closed position, but when pressure is released for opening the switch, sufficient pressure should be retained to keep the blades in alignment and to prevent vibration. The pressure is regulated by springs in conjunction with the differential release above mentioned. In switches of very high ampere capacity each spring assembly consists of a high pressure and a low pressure spring, so that the required pressures can be more readily obtained. The high pressure spring insures a pressure within the range required when the switch is in the closed and operating position, but when the switch is about to be opened the high pressure spring is entirely released, leaving only pressure exerted by the low pressure spring and which is more within the range of pressures required during the opening operation. On switches of lower ampere capacity it may be desirable to omit the low pressure springs.

Another advantage secured by the present invention is the equal distribution of pressure by reason of the line contacts on each side of the hinge and contact bolts, whereby, when pressure is applied at both the hinge and the contact, any slight misalignment of the hinge and contact bars with respect to the blade bars will be rectified. Spacing bushings between the blade bars intermediate their ends also provide for maintaining proper alignment thereof.

Another advantage of the present invention resides in the manner in which the blade bars are formed. During the forming operation the width of the bars is maintained constant, and thus the metal is caused to flow towards the ends and at the same time to flow into the raised contact portions of the bars, thus increasing the density of the copper at these contact portions and at the portions of the blades having minimum cross-section. This tends to maintain the current-carrying capacity of the blade bar more uniform throughout its length, and at the same time hardens the engaging portions of the blade bars so that there is less wear.

Other objects and advantages of the present invention will appear more fully from the following detailed description, which, taken in conjunction with the accompanying drawings, will disclose to those skilled in the art the particular construction and operation of a preferred form of our invention.

In the drawings:

Figure 1 is a plan view of the switch of the present invention, shown in its switch-closed or operating position;

Figure 2 is a side elevational view of the switch shown in Figure 1;

Figure 3 is a sectional elevational view of the switch shown in Figures 1 and 2, showing in detail the operating mechanism for the switch and the position which it assumes as the switch blades are about to be separated from the contacts; 5

Figure 4 is a sectional view through the hinge pivot bolt assembly, taken substantially on the line 4-4 of Figure 2;

Figure 5 is a sectional view of the contact end of the switch blade and the associated contact bars, taken substantially on the line 5-5 of Figure 2;

Figure 6 is a partial elevational view of the switch, showing the switch blade in its full open position; 15

Figure 7 is a sectional view taken on the line 7-7 of Figure 2, looking in the direction indicated by the arrows and showing in detail the contact and spring structure at the contact end of the switch blade; 20

Figure 8 is an elevational view of a modified form of contact blade;

Figure 9 is an elevational view of a second modified form of switch blade; and

Figure 10 is an elevational view of another 25 modified form of switch blade.

Referring now in detail to the switch shown in Figures 1, 2, 3, and 6, the supporting structure for the switch comprises a channel member, indicated at 10, which is provided with a pair of supporting insulators 11 and 12 of any desired construction, which insulators are bolted to the channel 10 and secured in non-rotative position thereon.

The upper end of the insulators 11 and 12 are 35 provided with cap portions adapted to receive the contact supporting casting 13 and the hinge supporting casting 14, respectively. These castings 13 and 14 are substantially U-shaped in section, having their base portions mounted upon the insulators 11 and 12 and secured in non-rotative engagement therewith by means of a plurality of bolts 16.

Considering now in detail the left-hand portion of the switch structure, the supporting casting 45 13 is adapted to support a plurality of contact bars arranged in pairs and mounted upon the upstanding arms 18 and 19 of the casting 13. These contact bars are indicated generally by the reference numeral 20, and are secured in 50 fixed position upon the arms 18 and 19 by means of a plurality of bolts 22. At their inner blade engaging ends, the contact bars 20 are provided with bevel portions 23 formed in their outwardly disposed face portions, which bevel portions extend a slight distance downwardly, as shown in detail in Figure 6. Also, the contact bars, as well as arms 18 and 19 of bracket 13, are provided with recessed portions or notches 24, having angularly extending defining edge portions 55 60 which are adapted to receive the contact bolts carried by the blade bars.

Considering now the hinge bars indicated at 25, these bars are substantially similar to the contact bars 20, and are mounted in fixed position upon the upstanding arms 26 and 27 of the supporting bracket 14 by means of a plurality of bolts 28. Both the contact bars 20 and the hinge bars 25 are provided with suitable openings 29 which are adapted to receive suitable securing means for mounting bus conductors or the like in electrical connection with the contact and hinge bars. 65 70

Referring now in detail to the construction of the switch member, the switch itself comprises 75

four blade bars, indicated by the reference numeral 30, which blade bars are arranged in pairs and provided, on the opposed facing surfaces of each pair, with pairs of raised contact portions, indicated at 31. These raised portions are formed by holding the blade bar in fixed position, with the upper and lower edges thereof supported against movement, and then applying suitable pressure to force the metal into the raised contact portions 31 and, at the same time, reducing slightly the cross-sectional area of that portion of the blade bars adjacent to and between the raised portions 31. The density of the copper in the reduced cross section is increased so that the carrying capacity has a tendency to remain constant throughout its entire length. In addition, the hardening of the contact surfaces 31 provides for eliminating wear upon these contact surfaces, this wear being taken up by the engaged surfaces of the contact bars 20 and the hinge bars 25, whereby replacement of these bars upon wearing thereof may be made instead of replacing the formed blade bars.

The hinge ends of the blade bars are mounted upon a pair of oppositely threaded stud members 35 and 36, as more clearly shown in Figure 4. These members have reduced threaded extensions which are coupled together by means of the internally threaded collar 37 of the lever 38. Suitable pin members 39 and 40 are driven through the reduced portions of the studs 35 and 36 to lock the collar 37 for conjoint movement thereon after the studs have been threaded into proper position. By securing the collar 37 for conjoint movement with the threaded extensions of the studs 35 and 36, rotation of the collar, due to movement of the lever 38, results in conjoint rotation of the studs.

As shown clearly in Figure 4, adjustable bushings 41 are threaded upon the inner portion of the studs 35 and 36 and extend into engagement with the hinge clamps 42 slidably mounted on the studs. The hinge clamps 42, which are of the form shown in elevation in Figure 2, are provided with normally extending shoulder portions 43, which engage over the upper and lower edges of the blade bar 30. This provides for conjoint rotation of the clamp 42 and the blade bar 30 about the stud. High and low pressure springs, indicated at 45 and 46, respectively, are interposed between the interior surface of the clamps 42 and the blade bars 30 at each end of the blade bars. These springs are substantially rectangular in shape, and are arcuately curved, the outer edges thereof bearing against the outer surfaces of the blade bars 30, and are adapted to press against the blade bars, urging them inwardly, upon the tensioning of the bushings 41. The inner blade bars 30 are positioned against the springs 45 and 46 and within the tongue portions 43 of the clamps 42, and the studs 36 and 35 are adapted to extend through two correspondingly drilled openings in the hinge bars 25 and the upstanding arms 26 and 27 of bracket 14. The outer blade bars 30 are secured in position over the outer ends of the studs 35 and 36, having bearing surfaces 31 engaging against the outer surfaces of the hinge bars 25, and a second set of high and low pressure springs 47 and 48, respectively, engage the outer surfaces of the blade bars 30 over the studs 35 and 36.

Corresponding hinge clamps 50, having normally extending lug portions 51, are slidably mounted on the outer ends of the studs 35 and 36 and are positioned over the upper and lower

edges of the outer blade bars 30. Adjusting bushings 52 extend over the outer ends of the studs 35 and 36, and the entire assembly may be tensioned with respect to the hinge bars 25 by tightening the bushings 41 and 52.

It will be noted that the portions of the studs 35 and 36 which receive the adjusting bushings 41 and 52, respectively, are oppositely threaded, so that upon rotation of the lever 38 in one direction, the bushings 41 and 52 will be moved apart by reason of the threaded engagement with the studs 35, whereas upon rotation of the lever 38 in the opposite direction, the bushings 41 and 52 will be threaded towards each other, thus serving to decrease and increase the tension upon the springs 45, 46, 47, and 48. The bushings 41 and 52 are provided with a plurality of radially extending slots or indentations 53 in their outer peripheries, which are adapted to receive suitable cap screws 54 threading into the hinge clamps 50 and 42, whereby the bushings may be threaded into proper position to tension the springs and the cap screws when applied to retain them in locked position with respect to the clamps 42 and 50, so that upon threading or unthreading of the bushings the clamps are moved conjointly therewith.

Referring now to Figure 5, which is a detailed view of the mounting of the switch blades at the contact ends thereof, the contact studs, or the studs employed at the contact ends of the blades, are indicated generally by the reference numerals 56 and 57. As shown in detail in Figure 7, the central portions of the studs are reduced in cross-section, in order to accommodate the studs within the recesses 24 formed in the contact bars and supporting arms 18 and 19. The inner ends of the studs 56 and 57 are provided with threaded extensions, which are adapted to be threaded into a collar portion 58 of an operating lever 59 having the ring portion 60 providing for engagement by any suitable switch operating device. Suitable pins 61 and 62 are driven through openings formed in the collar 58 and through the inner extensions of the studs 56 and 57 in order to lock the collar and studs together for conjoint movement after the studs have been properly positioned within the collar.

Adjustable bushing members 63 are provided, corresponding to the bushings 41 of Figure 4, and suitable blade clamps 64 are engaged over high and low pressure springs 45 and 46 and have normally extending shoulder portions engaging the upper and lower edges of the blade bars 30. In the same manner, the outer blade bars are engaged by high and low pressure springs 47 and 48 confined within the blade clamps 65, which blade clamps are secured in position by adjustable bushings 66 threaded onto the outer ends of the studs 56 and 57. It will be noted that the portions of the studs 56 and 57 which are engaged by the adjustable bushings 63 and 66, respectively, are oppositely threaded, in order to provide for conjoint inward and outward movement of these bushings with respect to the blade bars, to adjust the contact pressure thereof.

A release or latching mechanism for the switch is provided, which comprises the bar member 70, having a projecting latching portion 71 at one end thereof, and a bearing portion 72 provided with an adjusting set screw 73 at the opposite end thereof, the lever 70 being provided with an opening adapted to receive a pivot pin 74 which is enclosed by a cylindrical bushing member 75 about which is coiled a spring 76 anchored at its

outer ends, as indicated at 77, in the two inner blade bars 30 and bearing at its central portion against the under side of the release lever 70 to urge it in a counter-clockwise direction about the pin 74, which pin is supported between the inner set of blade bars.

In the assembly of the switch, the studs 35 and 36 are first passed through the openings in the brackets 26 and 27 and the openings in the hinge bars 25. The inner blade bars 30 are then passed over the studs 35 and 36, respectively, which extend through the openings in the blade bars, and the low and high pressure springs 46 and 45, respectively, are passed over the studs 35 up into engagement with the adjacent surfaces of the blade bars 30. The hinge clamps 42 are then inserted on the studs and the bushings 41 threaded onto the inner ends of the studs and into position to force the shoulders 43 of the clamps 42 over the top and bottom edges of the springs and blade bars.

The reduced inner end portions of the studs are then threaded into the collar 37 of the lever 38 and the pin members 39 and 40 driven through the reduced portions of the studs to lock the collar 37 thereon for conjoint movement with the studs.

The outwardly projecting ends of the studs 35 and 36 then receive the outer blade bars 30, high and low pressure springs 47 and 48, respectively, and the hinge clamps 50. The outer set of threaded bushings 52 are then threaded over the projecting ends of the studs.

With this much of the switch assembled, spacer members 80 and 81 are inserted between the blade bars 30 of each set of blade members and the pin 74 is extended through these bushings and through aligned openings in the two sets of blade bars to support the release or locking lever 40 and associated mechanism in position.

The contact end of the blade bars may be assembled in a similar manner, although because of the slots 24 in the arms 18 and 19 of the contact bracket 13 and the slots in the contact bars 20 it is not necessary to insert the studs 56 and 57 through these openings prior to assembly of the blade bars 30 thereon. Instead, the studs are passed through the openings in the respective pairs of blade bars, and the high and low pressure springs are applied over the studs against the outside surfaces of each set of blade bars. The hinge clamps 64 and 65 of each set of blade bars are then applied over the studs into engagement with the springs and the top and bottom edges of the bars. Then the adjusting bushings 63 and 66 are threaded over the opposite ends of each stud and the adjacent ends of the studs, which are of reduced cross section, are threaded into the collar 58 of the operating lever 59 and pinned in position as shown in Figure 5.

The adjustable bushings are then threaded inwardly on the studs to provide the proper amount of pressure at the hinge bars and the contact bars, the bushings 41 and 52 being tightened at the hinge end of the blade bars to produce a predetermined pressure of the blade bars against the hinge bars, these bushings then being locked in position by cap screws 54. Similarly, the bushings 63 and 66 are tightened and then locked in position by the cap screws 54. It should be noted that the blade bars are all identical in construction, and the raised contact surfaces thereof engage only the outer surfaces of the hinge and contact bars.

The switch is now assembled, and the operating

mechanism therefor is applied thereto by first moving the lever 38 to about its operating position and then tensioning the bushings 52 and 41 to provide the proper pressure at the hinge end of the switch.

When this has been done, the operating ring 59 and the lever 38 may be connected by the clevis member 84, which is pivoted at 85 about the operating lever 59, and which, at its opposite end, is adapted to receive an adjusting stud 86 which threads therewith, the adjusting stud 86 at its opposite end threading into a suitable socket 87 formed in the connecting link 88 pivoted at 89 to the extending end of the lever 38.

The opposite ends of the stud 86 are threaded in opposite directions so that by rotating the stud the proper adjustment may be secured between the operating lever 59 and the hinge lever 38. A suitable locking nut 90, carried by stud 86, is adapted to lock the members in position when final adjustment has been obtained.

Similarly, after the switch structure has been assembled, the ends 77 of the spring 76 are engaged in suitable openings formed in the inner members of each of the blade sets, as shown more clearly in Figures 8, 9, and 10, in which these openings are indicated by reference numeral 92. In the same figures, the openings in the blade bars which receive the pivot pin 74 are indicated by the reference numeral 93.

Referring now to Figures 1 and 2, in which the switch is shown in closed position, it will be noted that the operating lever 59 forms a toggle connection with lever 84 between the stud 56 and the pivot 89. Thus, when the operating lever 59 is moved to a position such that the pivot 85 is moved to or below the center line between the studs 56 and pivot 89, the switch is locked in operative position and cannot be jarred loose by vibration of the supporting channel 10 or similar external vibrations.

To open the switch, a suitable switch hook or the like is inserted in the ring 60 of the operating lever 59, and the operating lever is rotated in a clockwise direction to a position substantially as shown in Figure 3. Upon this rotation of the operating lever, the contact bolts or studs 56 and 57 are rotated therewith, and similarly, the connecting link 84, stud 86 and link 87 provide for rotation of the hinge lever 38, which in turn provides for conjoint rotation of the studs 35 and 36.

Due to the fact that the bushings 41, 52, 63, and 66 are locked to the blade clamps, and that these, in turn, are in fixed position relative to the blade bars 30, the bushings remain in a fixed position relative to the blade bars, and consequently rotation of the contact and hinge studs 35, 36, 56, and 57, causes a separation of the bushings along the studs due to the right and left-hand threads thereof. This releases the pressure at the hinge and contact.

It should be noted, however, that the operating lever 59 and the hinge lever 38 are so connected that the operating ring travels through an arc of approximately 120° while the hinge lever travels through an arc of only approximately 90°. This is due to the interconnection from the pivot 85 to the pivot 89, and to the fact that during a portion of the initial movement of the operating lever 59, no substantial movement of the lever 38 is effected when the pivot 85 is near the dead center position.

This differential of movement between the two levers provides for release of the contact pressure

between the contact surfaces 31 and the outer surfaces of the contact bars 20, but provides for retaining sufficient pressure at the hinge to maintain the blades in alignment and to prevent any lost motion or play at the hinge. The pressure at the contact is, however, not released to such an extent that the blades are entirely free from the contact bars, but just sufficient pressure is retained to prevent arcing at the contacts in case an attempt is made to open the switch while still under load. Further, this slight pressure between the contact surfaces 31 and the contact bars 20 is sufficient to clean the contact surfaces when the blades are opened or closed.

15 When the operating lever 59 has reached a position such that the desired amount of pressure release has been obtained, which can be adjusted by the bushings 41, 50, 63, and 66, a further rotation of the operating lever 59 from the position shown in Figure 3 results in moving the end portion 72 of the release lever 70 away from bearing engagement upon the base of the clamp or supporting bracket 13.

During the time that the switch has been in 25 operative position, as shown in Figure 2, the end 72 of the release lever 70, provided with the set screw 73, has been bearing against the base portion of the bracket 13 and consequently the lever 70 has been forced in a clockwise direction such 30 that the latching portion 71 thereof has been moved downwardly with respect to the stud bolts 35 and 36.

As clearly shown in Figure 3, the lever 38 is provided with a projecting portion 92, which, 35 together with a second projecting portion 93, defines a recess or notch 34 in which the lug 71 of the lever 70 is adapted to engage. This lug is disengaged during all times that the blades are in their contact engaging position, and consequently, during the initial switch opening movement of the operating lever 59, the lever 38 is free to rotate and to rotate the studs 35 and 36 therewith. However, when the lever 59 reaches a 40 position substantially as shown in Figure 3, any further rotation thereof provides for abutment of the projecting portion 92 against the end 71 of the lever 70, so that a continued pull on hook stick in eye 60 will cause the blades to rotate 45 towards their switch open position.

50 Upon such initial movement of the blades, the bearing 72 is raised and consequently the spring 76 urges the lever 70 in a counterclockwise direction to engage the lug portion 71 within the notch 34, thereby preventing any further rotation of the lever 38. The mechanism is now latched in 55 fixed position, and further movement of the operating lever 59 serves only to rotate the entire switch blade mechanism about the hinge studs 35 and 36 bearing within the openings in the hinge bars 25 when the switch is moved to the 60 position shown in Figure 6, which is its full open position. No further rotation of the studs can be effected.

It is understood, however, that the mechanism 65 is so adjusted that a slight rotating movement of the blades downwardly from the position shown in Figure 3 unlocks the release lever from engagement with the hinge lever, so that the blades may be returned to closed position and 70 clamped by pressure against the contact bars 20 if, for any reason, it is decided that the switch should not be opened.

The reduced intermediate portions of the studs 75 56 and 57 are for the purpose of reducing, to as great an extent as possible, the size of the re-

cesses 24 which must be formed in the contact bars 20 and the supporting arms 18 and 19 of the brackets 13.

As the switch is moved to its full open position the pressure at the hinged studs 35 and 36, effected by the springs 46 and 48, is maintained, due to locking of the studs against further rotation with respect to the blade bars, and is just sufficient to prevent the blades from rattling and to hold the switch in proper position against vibration and the like. This low frictional engagement of the contact portions 31 of the blades about the hinge bars is maintained until the contact ends of the blade bars 30 begin to engage within the groove or notch 24 of the contact bars 20, at which time the locking engagement between the lever 70 and the lever 38 is released, and rotation of the operating lever 59 results in applying pressure simultaneously at both the hinge bars and the contact bars. However, due to the differential movement therebetween, the pressure at the contact bars is increased so that it becomes substantially equal to that at the hinge bars in order to provide for proper contact between the contact bars 20 and the blade bars 30.

It will be noted that the blade bars 30, with their corresponding raised contact surfaces 31, swing about the hinge bolts 35 and 36 in such manner as to have substantially full surface contact over the entire surface of the hinge bars adjacent this point. This is due to the fact that these line contacts sweep over this surface while being angularly rotated. However, this same action is not effected at the contact ends of the blade bars, since these ends move only in a relatively restricted arc, during a limited portion of the rotation of the blade member, across the surface of the contact bars 20. If the pressure adjustment is not properly maintained, or if the switch is operated a considerable number of times, the line contacts may have a tendency to wear grooves in the contact bars.

To overcome this tendency we have provided several modified forms of blade bars, in which the line contacts at the contact ends of the blade bars are so formed as to remove almost entirely any tendency of the blade bars to wear grooves in the corresponding contact bars. For example, by angling the contact surfaces 98, which correspond to the contact surfaces 31 previously described, in the manner shown in Figure 8, the contact surfaces will bear across a certain area of the contact bars and there will be little or no tendency to wear grooves in the bars, since the contacts 98 sweep across the surface of the bars in a lateral direction. The same result is effected by angling the contact surfaces in the opposite direction, as shown at 99 in Figure 9. If desired, the contact surfaces can be formed horizontally of the blade bars, as shown at 100 in Figure 10, in which case they sweep across the surface of the contact bars over an area determined by their length and the arc of rotation, thus eliminating any tendency for grooves to form in the contact bars.

It is obvious that any desired type of projecting contact surfaces may be provided for this purpose, and we do not intend to be limited to the particular form shown in connection with the operating characteristics of the switch.

By the provision of the high and low pressure 70 springs, together with the hinge and contact blade clamps mounted in position and tensioned by the adjustable bushings carried on the hinge and contact bolt assemblies, it is possible to pro-

vide for any desired pressure at both the hinge end and the contact end of the blade bars.

Further, by the provision of the differential action between the operating lever and the hinge lever, it is possible to release almost entirely the pressure at the contact end of the blades, while retaining sufficient pressure at the hinge end of the blades to prevent rattling or vibration of the blades when they are moved into their open position. Also, the latching means, which is effective upon movement of the operating member to a position to release the blades from engagement with the contact bars, provides for conjoint movement of the entire switch assembly to open position after the contact pressure has been sufficiently released. With the adjustable bushings, this contact pressure may be varied as desired, and consequently the switch operating structure is capable of a wide range of desired contact pressures.

Certain other features which lend practicability to our switch structure are the provision of the right- and left-hand threads interconnected by the operating mechanism whereby movement of the single operating rod provides for conjoint inward or outward movement of the adjusting bushings to release or increase the bearing or contact pressure at the hinge and contact ends of the blade bars.

We do not intend to be limited to the exact details shown and described in connection with the illustrated embodiment of our invention, as we are aware that certain modifications and changes in the design and cooperating relation of the various elements embodied in our switch structure can be made without departing from the spirit of the present invention, and we therefore intend to be limited only as defined by the scope and spirit of the appended claims.

We claim:

1. A switch comprising hinge bars, blade members pivotally mounted in laterally spaced position on opposite sides of each of said bars, clamping means engaging the opposite faces of each set of said blade members, means interposed between said clamping means and said blade members for preventing vibration between said blade members and said hinge bars when said blade members are in open position, and means comprising a stud having oppositely threaded portions engaging said clamping means to move the same toward each other to provide high pressure contact between said hinge bars and blade members when said members are in switch closed position.

2. In combination, in a switch, a supporting structure, hinge bars and contact bars mounted in spaced relationship on said structure, a plurality of pairs of switch blade bars pivoted at one end about opposite sides of said hinge bars, and means between said pairs of blade bars for swinging said blade bars into engagement with said contact bars, said means being adapted upon continuous switch-closing motion to apply a first predetermined pressure between said hinge bars and each pair of blade bars and a second predetermined pressure between said contact bars and each pair of blade bars, and being adapted upon switch-opening movement to initially release the pressure at the contact bars to a greater extent than at the hinge bars and to thereafter prevent any release of pressure at said hinge bars.

3. In combination, in a switch, hinge bars and contact bars mounted in spaced relation, switch blade bars pivoted at one end on said hinge bars, means for swinging said blade bars into engage-

ment with said contact bars, and clamping means adapted upon continuous motion of said swinging means to produce a first predetermined pressure between said hinge and blade bars, and a second predetermined pressure between said contact and blade bars, said clamping means being rotated through relatively different arcs by said motion of said swinging means.

4. A switch blade construction comprising a pair of spaced blade bars, hinge bars for one end of said blade bars, stud means for pivotally supporting said one end of said blade bars on said hinge bars, a threaded stud extending through said blade bars at the opposite end thereof, contact bars adapted to be engaged between said opposite ends of said blade bars, and interconnecting means for rotating said stud and stud means rotatable through different arcs of rotation to urge said opposite ends of said blade bars into and out of high pressure engagement with said contact bars and hinge bars, said means being interlocked during a portion of the movement thereof whereby predetermined minimum pressure is maintained on said hinge bars at all times.

5. In combination, in a switch of the class described, contact bar means, hinge bar means, spaced blade bars extending therebetween on opposite sides thereof and having restricted line contact surfaces engaging the outer surfaces of said bar means, threaded stud means for pivotally supporting said blade bars on said hinge bar means, corresponding stud means extending through said blade bars at the contact ends thereof, pressure applying means carried by said two last named studs, and operating means interconnected between said stud means and operable to rotate the same during initial switch opening movement, said operating means rotating said first stud means through a smaller angle than said second stud means to effect a correspondingly successive release of pressure at the hinge and contact ends of said blade bars.

6. In combination, in a switch of the class described, contact bar means, hinge bar means, spaced blade bars extending therebetween, threaded stud means for pivotally supporting said blade bars on said hinge bar means, corresponding stud means extending through said blade bars at the contact ends thereof, pressure applying means carried by each of said stud means, operating means interconnected between said stud means and operable to rotate the same during initial switch opening movement, said operating means rotating said first stud means through a smaller angle than said second stud means, and means operable upon initial movement of said blade bars away from said contact bar means for locking said operating means for conjoint movement with said blade bars to prevent further rotation of said stud means during the remainder of said switch opening movement.

7. In a switch blade adapted for swinging movement into and out of engagement with fixed contact means, a pair of spaced blade bars, a threaded stud member at the hinge end of said blade bars, a second threaded stud member at the contact end of said blade bars, means carried by said stud members and adapted upon rotation thereof to be moved inwardly and outwardly for increasing and decreasing the pressure between said blade bars and said hinge supporting means and contact means, and means interconnected between said stud members and adapted upon a predetermined rotation thereof to effect a relatively different degree of rotation

of said stud means to apply a substantially equal pressure at the contact end of said blade bars and at the hinge end thereof in switch closed position and to produce a predetermined difference in pressure between the hinge end and contact end of said blade bars upon switch opening movement.

8. A switch comprising a blade member, a hinge support therefor, a contact bar adapted to be engaged by said blade member, a threaded stud supporting said blade member on said hinge support, a second threaded stud at the contact end of said blade member, means interconnected between said studs for rotating the same during initial switch opening movement, and locking means operable upon predetermined rotation of said hinge stud for locking said stud means together to prevent further rotation thereof and to provide for separation of said blade member and movement thereof into switch open position upon further actuation of said interconnected means.

9. A switch comprising a blade member, a hinge element therefor, a contact bar, stud means at the hinge end and contact end of said blade member, high and low pressure spring means interposed between said stud means and the surfaces adjacent the ends of said blade member, clamping means carried by said stud means and engaging said spring means and adapted to urge said spring means against said blade members upon rotation of said stud means, means for rotating said stud means to apply pressure through said spring means to said blade members, said low pressure spring means being operable upon release of said pressure for holding said blade member against vibration.

10. A switch comprising a contact terminal, a hinge terminal, blade bars hinged on said latter terminal and movable into and out of engagement with said first terminal, clamping means on said bars at the terminal ends thereof, rocker arms for actuating each of said clamping means, and interconnected actuating and release means providing for conjoint movement of said arms to swing said blade bars into and out of engagement and for relative movement of said arms when in contact engaging position.

11. A switch comprising a contact terminal, a hinge terminal, blade means carried by said hinge terminal and movable into and out of contact with said contact terminal, clamping means for producing pressure engagement of said blade means with said terminals, actuating means for each of said clamping means, and means interconnecting said actuating means whereby one of said actuating means has predetermined movement relative to the other actuating means to produce a relative difference in clamping action at said terminals.

12. A switch comprising a contact terminal, a hinge terminal, blade means carried by said hinge terminal and movable into and out of contact with said contact terminal, clamping means for producing pressure engagement of said blade means with said terminals, actuating means for each of said clamping means, means interconnecting said actuating means whereby one of said actuating means has predetermined movement relative to the other actuating means to provide a relative difference in clamping action at said terminals, and means operable upon predetermined movement of said other actuating means during switch-opening movement of said interconnecting means to prevent further movement

of either of said actuating means for effecting swinging movement of said blade means out of engagement with said contact terminal.

13. A high tension switch including a pair of spaced terminals, switch blade means in said one terminal and movable into and out of engagement with the other terminal, means engaging said blade means for moving the same into substantially equalized contact pressure with each of said terminals, said means being releasable upon switch-opening movement and prior to arcuate movement of said blade means to decrease the pressure at one terminal to a greater extent than at the other terminal.

14. In combination, a contact terminal, a hinge terminal, blade means pivotally supported on said hinge terminal and movable into and out of engagement with said contact terminal, clamping means at the hinge and contact ends of said blade means, and interconnected means operable to produce a successive movement of said clamping means during predetermined movement for producing a greater clamping pressure at the contact end of said blade means than at the hinge end thereof when said blade means is in contact engaging position.

15. In combination, a contact terminal, a hinge terminal, blade means pivotally supported on said hinge terminal and movable into engagement with said contact terminal, clamping means at the hinge and contact ends of said blade means, rocker arms for actuating each of said clamping means, and means interconnected between said arms for producing an increased clamping pressure at one of said arms.

16. In combination, a contact terminal, a hinge terminal, blade means pivotally supported on said hinge terminal and movable into and out of engagement with said contact terminal, clamping means at the hinge and contact ends of said blade means, rocker arms for actuating each of said clamping means, and means for actuating said arms including means for rotating one of said arms through a greater arc than the other of said arms.

17. In combination, a contact terminal, a hinge terminal, blade means pivotally supported on said hinge terminal and movable into and out of engagement with said contact terminal, clamping means at the hinge and contact ends of said blade means, rocker arms for actuating each of said clamping means, and means interconnecting said arms for conjoint movement in switch opening direction only after said arms have been successively rotated through arcs to effect a corresponding sequential release of the associated clamping means.

18. In combination, U-shaped contact and hinge brackets, contact and hinge bars carried thereby, a plurality of pairs of blade bars on opposite sides of said hinge bars, studs pivoting said pairs of blade bars on said hinge bars, said studs having oppositely threaded ends, clamp means threaded on said studs and held against movement with respect to said blade bars, a rocker arm non-rotatably secured over the adjacent ends of said studs for rotating said studs to move said blade bars into and out of pressure engagement with said hinge bars, corresponding studs and clamping means at the contact ends of said blade bars, a second rocker arm connected to the studs at the contact end of said blade bars for moving said blade bars into and out of pressure contact with said contact bars, an over-reaching interconnecting means between said

- arms whereby one of said arms in moving through a predetermined angle produces a different angular movement of said other arm, and releasable means engaged after predetermined movement of one of said arms locking said arms for conjoint movement to effect separation of said blade bars from said contact bars.
19. A switch comprising a hinge bar, a switch blade bar pivotally mounted at one end on said hinge bar, a contact bar adapted to be engaged by the opposite end of said blade bar, clamping means at opposite ends of said blade bar and rotatable through different arcs of rotation to effect different clamping pressures at the opposite ends of said blade bars, and interconnecting means between said clamping means and operable upon initial switch opening movement to release the clamping pressure between said blade bar and contact bar and to reduce the clamping pressure between said blade bar and hinge bar and thereafter interlocking said clamping means to prevent further decrease of pressure between said hinge bar and blade bar during continued switch opening movement.
20. Operating means for a switch blade of the class described including clamping means at the hinge and contact ends of said blade, said operating means comprising a pair of interconnected arms movable through different arcs of rotation in switch opening movement to effect a relatively different release of clamping pressure at opposite ends of said blade, and means carried by said blade and operable upon movement thereof out of switch-closed position for thereafter interlocking said arms against further pressure-releasing movement as said blade is moved into switch open position.
21. Operating means for a switch blade of the type having one end hinged for pivotal movement of said blade into and out of switch closed position, means for maintaining a predetermined minimum clamping pressure at the hinge end of said blade throughout swinging movement of said blade and a substantially reduced pressure at the contact end of said blade and means for increasing the pressure at said hinge end a predetermined amount as said blade moves into switch closed position including interconnected means for producing a corresponding predetermined pressure at the contact end of said blade after said blade has moved into switch closed position.
22. Operating means for a switch blade of the type having one end hinged for pivotal movement of said blade into and out of switch closed position, means for maintaining a predetermined minimum clamping pressure at the hinge end of said blade throughout swinging movement of said blade and a substantially reduced pressure at the contact end of said blade and means for increasing the pressure at said hinge end a predetermined amount as said blade moves into switch closed position including interconnected means for producing a corresponding predetermined pressure at the contact end of said blade after said blade has moved into switch closed position, said last-named means providing for initial release of the clamping pressure at the contact end of said blade upon initial switch opening movement of said interconnecting means and reduction of said pressure at the hinge end of said blade to said predetermined minimum.
